Inventor:

Warren A. Simonds.

UNITED STATES PATENT OFFICE.

WARREN A. SIMONDS, OF BOSTON, ASSIGNOR TO HIMSELF AND S. G. B. COOMBS, OF SOUTH READING, MASSACHUSETTS.

IMPROVED APPARATUS FOR CARBONIZING AIR FOR ILLUMINATING PURPOSES.

Specification forming part of Letters Patent No. 43,264, dated June 21, 1864.

To all whom it may concern:

Be it known that I, WARREN A. SIMONDS, of Boston, in the county of Suffolk and State of Massachusetts, have invented a new and Improved Method for Carbonizing Air for Illuminating Purposes; and I do hereby declare that the following is a full and exact description thereof, reference being had to the accompanying drawings, and to the letters of reference marked thereon.

The nature of my invention consists in the construction of a cylinder-shaped vessel or reservoir, set horizontal in a suitable frame, with two, four, six, or more partitions so arranged that the said reservoir may be divided into several equal compartments, with an independent sectional wheel to revolve in each compartment, the shaft of which to have a bearing in the center of each end of said vessel or reservoir, through which air may be forced with a pump or bellows attached to gear-wheels and operated with weights or springs for carbonizing the air for illuminating purposes.

To enable others skilled in the art to make and use my invention, I will proceed to describe its construction and operation.

Figure 1 is a perspective view of my apparatus as used for carbonizing the air for illuminating purposes.

Letter A is a reservoir of a cylinder shape fastened into frame E.

Letter B is a pressure-meter or pump, connected at the outlet c with lead pipe to the inlet d on the carbonizer A.

Letter D is a frame connected to one end of frame E for the shafting and gear-wheels, and so arranged that they may be operated with a chain and weights (very much like a clock) and operate both the meter B and the sectional wheel within the cylinder A by being connected with gear-wheels to the shaft L at one end of cylinder A, and to the shaft f, which projects through the top part of frame D.

Letter C represents a reservoir or holder for the reception of carbonized air after being forced through cylinder A and its compartments 1 2 3 4, previous to its distribution through pipes to the burners. It also answers as a regulator to the pressure of air, and gas-cock 1, near the bottom of one end of reservoir

A, is for drawing off the liquid when too heavy for vaporization. Cock 2 upon the upper end of pipe 3 is for filling the reservoir A about one-third full, or to the vent-cock 3, which should be open while filling said vessel or reservoir with very light and volatile naphtha, such as is produced from coals or petroleum oils.

To operate the above machine or apparatus, cylinder A should first be filled with very light and volatile naphtha, through cock 2, about one-third full, which cock 3 will indicate when open; then wind up the chain h with sufficient weight attached to one end over the spigot-wheel 4 on the lower shaft, with a crank-key upon the shaft 5, after which the air will be forced from the pressure-meter or pump B, through outlet c and inlet d, into and through the top of one end of cylinder A into chamber 1, through which the air is forced downward and through the fibrous material attached to a section of wheel H, in each compartment under partition a, into chamber 2, through which it passes upward through a second section of wheel H over partition b into chamber 3; thence downward through third section of wheel H and under partition a into chamber 4, up and through the fourth section of wheel H, to and through the outlet 8, into the reservoir and regulator C, from which it is forced through pipes to the burners.

A represents an interior and sectional view of the reservoir or carbonizer with its partitions, shaft, and sectional wheel. Partitions a a are arranged crosswise of the cylinder and soldered upon the inside tight around the top and sides downward to within about one and one-half inch of the top of shaft L. b is a partition with an aperture or opening straight across the top and bottom of about one and one-half inch, and soldered tight around the sides with a hole in the center for the shafts to revolve. H H H H are wheels with two sets of spokes, one set at each end of the hub of each wheel, which are made fast to shaft L. Each spoke is perforated with holes close together and at right angles with each other, for the purpose of working cotton wicking or other fibrous material through all the holes in a circular form from the hub to the end of the spokes, and likewise the same at right angles or across from one spoke to its opposite on the

same hub, and said wheels to be of such diameter and width, when attached to the shaft L, as not to rough or create friction when made to revolve in the chambers and between the partitions *a b a*, inside of the cylinder or reservoir A. Shaft L has a bearing upon the inside and center of head P, and passes horizontally through the center of said cylinder and partition *b*, and through head S, upon which is a stuffing-box to be made tight around shaft L, said sectional wheel to revolve through volatile liquids for facilitating in the vaporization when used for the purpose herein described.

Fig. 2 is a perspective end view showing the frame E, with the cylinder A fastened thereon.

Fig. 3 represents an end view of the construction of the sectional wheels used for assisting in the vaporization of volatile liquids for carbonizing the air for illuminating purposes.

I do not claim as my invention a single or undivided cylinder; but

What I claim as my invention, and desire to secure by Letters Patent, is—

1. The cylindrical vessel or reservoir divided into chambers, with partitions arranged and constructed as herein set forth and described.

2. The construction and arrangement of a sectional wheel when operated as herein specified.

3. The sectional wheel made fast to the shaft L, when arranged within a sectionally-divided vessel or reservoir, and operated for carbonizing the air for illuminating purposes, as herein specified and set forth.
